SHUTTLE FOR AUTOMATIC LOOMS

Richard G. Turner, Worcester, Mass., assignor to
Crompton & Knowles Loom Works, Worcester,
Mass., a corporation of Massachusetts

Application January 2, 1937, Serial No. 118,787

4 Claims. (Cl. 139—207)

This invention relates to improvements in automatic looms and more particularly for means for preventing spring clips from spreading due to momentum of the bobbin when the shuttle is boxed.

When bobbins oval in transverse section are used it is necessary to maintain the long transverse axis horizontal. If this axis becomes vertical the lower edge of the weft projects below the bottom of the shuttle and interferes not only with correct shuttle boxing, but also interferes with the lower sheet of warp threads during the flight of the shuttle.

It has been discovered that there is a tendency on the part of a bobbin to rotate about its longitudinal axis during weaving, particularly when a bobbin is held by means of spring jaws which engage rings on the head of the bobbin. An angular motion sufficient to give the bobbin a quarter turn would place the long transverse axis vertical and interfere very objectionably with the proper picking of the shuttle and result also in damage to the lower part of the mass of weft.

The shuttle moves at a high rate of speed and is brought to rest abruptly by engagement with the picker. This stopping of the shuttle motion is attended with considerable shock and as a result there is a tendency on the part of the bobbin to continue movement in the direction of travel of the shuttle due to its momentum. Because of the shape of the contacting surfaces between the rings and the spring jaws the latter spread slightly due to the fact that the bobbin tends to continue its motion when the shuttle is abruptly stopped. When the momentum of the bobbin is spent the jaws move back to their normal position. If at this time the spring forces acting on the bobbin are not balanced there will be a slight turning moment tending to rotate the bobbin about its longitudinal axis.

It is an important object of my present invention to prevent the aforesaid slight spreading of the jaws when the shuttle is boxed. As set forth hereinafter I accomplish this result by providing the shuttle with resilient blocks of rubber or the like which are sufficiently strong to resist spreading of the jaws by any force which may be exerted by the rings of the shuttle against the bevelled grooves of the jaws incident to boxing. The blocks, however, are sufficiently resilient to yield under the positive force exerted by the transerrer at the time a new bobbin is being inserted into the shuttle. By provision of these means I maintain close contact between the rings of the bobbin and the spring jaws of

the shuttle when the latter is being boxed and therefore eliminate possibility of the bobbin turning on its axis.

With these and other objects in view which will appear as the description proceeds, my invention resides in the combination and arrangement of parts hereinafter described and set forth.

In the accompanying drawing, wherein a convenient embodiment of my invention is set forth,

Fig. 1 is a top plan view of one end of a lay 10 showing a shuttle made according to my present invention,

Fig. 2 is a vertical section on an enlarged scale on line 2—2, Fig. 1,

Fig. 3 is a diagrammatic view illustrating the transfer mechanism, and

Fig. 4 is a horizontal section on line 4—4 of Fig. 2.

Referring more particularly to Fig. 1, I have shown a loom lay 10 having a shuttle box B to 20 receive a shuttle S provided with a bobbin 11. The bobbin may be of the so-called oval or flat type wherein the barrel on which the weft W is wound has a horizontal transverse dimension greater than the vertical dimension and the weft 25 takes the general form indicated in Fig. 2.

The bobbin has a head 15 provided with the customary metal rings 16 which are received by a spring clip 17 having front and rear jaws 18 and 19, respectively. These jaws are grooved in the usual manner, a suggested in Fig. 4, to receive the rings 16. The rings and the wooden head of the bobbin on which they are mounted, together with the spring clip 17 are of the usual construction. The box B has a shuttle binder 20 and a binder spring 21 and the shuttle is propelled by a picker 22 in the usual way.

When the shuttle is boxed it strikes the picker 22 with considerable force and is brought to rest abruptly, since the picker lies against the box end 23. As a result the bobbin, because of its momentum, tends to move toward the picker and the round rings bearing against the bevels 25 of the sides of the grooves 26 tend by reason of the force exerted due to momentum to spread the jaws slightly. This force is not very large but is sufficient to cause a temporary separation of the jaws 18 and 19.

The matter thus far described is of known construction and of itself forms no part of my present invention.

In carrying my invention into effect, I provide the shuttle with blocks 30 of slightly resilient rubber which are interposed between the front and back shuttle walls 31 and 32, respectively, 55

as shown, and the jaws 18 and 19, respectively. These blocks may be recessed into the shuttle walls or held therein in any other approved manner. The blocks 30 bear against the outer 5 vertical walls of the adjacent jaws and create sufficient resistance to prevent spreading of the shuttle by momentum of the bobbin when the shuttle is boxed.

It is necessary to make provision for transferring a new bobbin into the shuttle, and this 10 result may be accomplished as shown in Fig. 3 by a transerrer arm 40 movable about a pivot 41 and is actuated by a latch 42 pivoted to the arm at 43 and movable by mechanism not shown but 15 well understood into the path of the dagger 44 on the lay. A reserve bobbin 50 is presented in any approved manner under the transerrer arm when a transfer is to take place. The advancing lay depresses the rear end of the transerrer arm to 20 force the reserve bobbin 50 against the bobbin lever. At this time the blocks 30 will not be able to prevent spreading of the spring jaws under the action of the positive force exerted by the transerrer arm, and the reserve bobbin 50 will therefore 25 pass into the shuttle and the depleted bobbin 11 will be expelled downwardly through a slot 51 in the lay. As soon as the transferring action is completed the blocks 30 will spring back to their normal condition where they are effective to 30 resist a separation of the jaws when the shuttle is boxed.

It is to be understood that my present invention contemplates a particular relationship between three forces the strongest of which is exerted by the transerrer arm through the incoming bobbin and the weakest of which is exerted by the momentum of the bobbin tending to spread the jaws when the shuttle is boxed. Lying intermediate these two forces is the 35 resistance offered by the blocks 30, these blocks being strong enough to resist compression when the shuttle is boxed, but yielding sufficiently to permit a normal transfer when the transfer arm 40 descends.

From the foregoing it will be seen that I have 40 provided a shuttle wherein the spring jaws are prevented from separation by engagement with the slightly resilient means interposed between the jaws and the walls of the shuttle when the 45 shuttle is boxed. It will also be seen that the resistance offered by these resilient means represents a force which lies between that exerted by the transerrer arm and the force of the momentum derived from the bobbin when the shuttle 50 is boxed.

Having thus described my invention it will be 55 seen that changes and modifications may be made therein by those skilled in the art without depart-

ing from the spirit and scope of the invention and I do not wish to be limited to the details herein disclosed, but what I claim is:

1. In a shuttle for an automatic loom, integral spaced resilient bobbin holding jaws mounted in 5 the shuttle, a bobbin having rings held by the jaws and tending by the momentum thereof to spread the jaws apart when the shuttle is boxed, and a block of slightly resilient material for each jaw, each block located between and contacting 10 the corresponding jaw and an adjacent part of the shuttle adjacent to the rings, said blocks resisting the tendency of the jaws to spread apart when the shuttle is boxed.

2. In a shuttle for an automatic loom, integral spaced resilient bobbin holding jaws mounted in the shuttle, a bobbin head with rings held by the jaws and tending by the momentum thereof to spread the jaws apart when the shuttle is boxed, and a block of slightly resilient rubber for 20 each jaw, each block of rubber engaging the shuttle and also the corresponding jaw adjacent to the rings on the head, said blocks resisting the tendency of the jaws to spread apart when the shuttle is boxed.

3. In a shuttle for an automatic loom, a pair of integral resilient substantially parallel jaws mounted in the shuttle and extending along walls of the shuttle and having grooves therein, a bobbin having a head provided with rings to 30 enter the grooves of the jaws, said bobbin tending by its momentum to spread the jaws apart when the shuttle is brought to rest, and a block of resilient material between each jaw and the adjacent shuttle wall acting in addition to the 35 resilience of the jaws to prevent separation of the latter by the momentum of the bobbin, said blocks being located between the grooves in the jaws and the adjacent shuttle walls.

4. In a shuttle having spaced vertical walls, a 40 spring member mounted in the shuttle and having two spaced resilient integral jaws, each jaw extending along one of the walls, each jaw having transverse grooves therein on the sides thereof opposite the adjacent wall, a bobbin having 45 a head provided with holding rings which enter the grooves in the jaws, the momentum of the bobbin tending by reason of contact between the rings and the jaws to spread the latter when the shuttle is brought to rest, and a block of rubber between each jaw and the adjacent shuttle wall, each block of rubber engaging the corresponding jaw along the surface opposite the grooves thereof and acting in addition to the resilience of the jaws to resist spreading of the latter by the bobbin 50 when the shuttle comes to rest.

RICHARD G. TURNER.
